UNITED STATES PATENT OFFICE.

NICOLA TURTURRO, OF NEW YORK, N. Y.

DESIGN FOR A GUITAR OR SIMILAR ARTICLE.

Application filed June 3, 1922. Serial No. 2,513. Term of patent 14 years.

To all whom it may concern:

Be it known that I, NICOLA TURTURRO, a citizen of the United States, residing at New York city, county of Bronx, and State of New York, have invented a new, original, and ornamental Design for Guitar or Similar Article, of which the following is a specification, reference being had to the accompanying drawings, forming part thereof.

Fig. 1 is a front view of the article showing my new design; and

Figs. 2 and 3 are respectively side and back views of the body of the instrument.

The dominant feature of the design consists in the shape of the body of the instrument.

I claim:

The ornamental design for a guitar or similar article, as shown and described.

NICOLA TURTURRO.
